UNITED STATES PATENT OFFICE.

JOHN D. STIRCKLER, OF BOSTON, MASSACHUSETTS, ASSIGNOR TO THE CONSOLIDATED FASTENER COMPANY, OF PORTLAND, MAINE.

FASTENER-MAKING MACHINE.

SPECIFICATION forming part of Letters Patent No. 668,395, dated February 19, 1901.

Application filed May 1, 1900. Serial No. 15,152. (No model.)

To all whom it may concern:

Be it known that I, JOHN D. STIRCKLER, a citizen of the United States, residing at Boston, in the county of Suffolk and Commonwealth 5 of Massachusetts, (post-office address 468 Summer street, East Boston,) have invented a new and useful Improvement in Fastener-Making Machines, of which the following is a full specification.

10 My invention relates to machines for forming a contracted neck on the eyelet or stud of the fastener; and it consists of certain details of construction hereinafter shown and described.

15 In the drawings I have shown my machine for forming the contracted neck on the ball member of the fastener.

Figure 1 shows a vertical section of the upper and lower dies of my machine with the eyelet or stud held on the lower die before being operated upon. Fig. 2 shows the same after the dies have been brought together, forming a neck on the stud. Fig. 3 shows the stud before the neck is formed in it, and Fig. 4 the 25 same provided with a neck. Fig. 5 shows a plan of the under side of the upper die of my machine.

Referring to the drawings, the upper die A consists of a hollow sleeve C, suitably held in 30 the plunger of my machine and having at its lower end a conical concavity.

Inserted in the inside of the sleeve C is the collet-piece D, which is constantly urged outward by the spiral spring E, between this end 35 and the adjusting-screw c, screwed into the upper end of the sleeve C. Although urged outward, the outward motion of this collet-piece D is limited by the stop-pin d playing in the slot c' of the sleeve C.

40 The lower end of the collet-piece D flares outward into a cone corresponding to the conical concavity in the end of the sleeve C. The lower end of the piece D is also kerfed, so that it is really formed of a number of spring-fingers, which may be contracted, and, as will be 45 seen in the drawings, these fingers will be contracted when the piece D is thrust back into the sleeve C against the action of the spring E.

In the lower end of the piece D is cut the

cavity d', large enough to admit the stud X, 50 as shown in Fig. 3, and so shaped that when the fingers of the piece D are contracted this cavity d' will have just the shape of the stud with the neck x.

The stud X is held on the lower die B, having the teat b, supporting the inside of the stud in height, and having a diameter small enough to allow it to be withdrawn after the neck x is formed.

By means of the spring E and the stop d I am 60 enabled to adjust my machine very nicely in order to insure an even and uniform product.

As will be readily understood, the stud x having been placed on the teat b, the plunger is lowered until the lower face of the collet-piece D contacts with the flange of the stud. Further downward movement of the sleeve then acts on the spring E, thereby practically storing power while the collet-piece is being moved to shape the stud. The arms of the 70 collet being arranged to spread automatically when under the action of the conical concavity, it will be seen that upon the return movement of the sleeve C (which is aided by the stored power of the spring) the spring E will 75 hold the collet-piece against the flange of the stud until said piece has spread to a point where it can be raised without tending to take the stud from off its teat.

I claim—

1. In a fastener-making machine, a die consisting of a sleeve C having a conical concavity, the piece D having an external conical end and neck provided with a central forming-concavity in combination with a spring 85 E and stop d substantially as shown and described.

2. In a fastener-making machine, the combination of a die consisting of a plunger, a sleeve mounted therein, said sleeve having a 90 conical concavity at its lower end, a collet-piece mounted to have a sliding movement in said sleeve, the lower end of said piece having an external cone-shaped face adapted to be acted upon by said conical concavity to 95 compress the piece, a central forming-cavity formed at the lower end of said piece, a spring for normally holding the lower end of said

collet-piece in an inoperative position, a stop, and means for forming an abutment against which the lower face of said collet-piece contacts, thereby storing power during the forward movement of the plunger for retaining said piece against a return movement until in a position to return.

In witness whereof I have hereunto set my hand.

JOHN D. STIRCKLER.
